UNITED STATES PATENT OFFICE.

EUGÈNE SCHNEIDER, OF LE CREUZOT, FRANCE.

MEANS FOR CONNECTING TOGETHER THE FLOAT AND THE SINKER OF A SUBMARINE MINE.

1,244,377.

Specification of Letters Patent. Patented Oct. 23, 1917.

Application filed December 9, 1916. Serial No. 136,118.

To all whom it may concern:

Be it known that I, EUGÈNE SCHNEIDER, a citizen of the Republic of France, residing at Le Creuzot, France, have invented certain new and useful Improved Means for Connecting Together the Float and the Sinker of a Submarine Mine, which is fully set forth in the following specification.

This invention has for its object to provide improved means more particularly applicable to submarine mines which are intended to be "sown" by a submarine, and generally to mines which before being "sown" are attached to the mine-sowing vessel by means of rollers or other members engaged in rails or other guides carried by the said vessel.

These improved means are designed on the one hand to assure a rigid connection of the float to the sinker up to the instant when, for casting off the mine, the mine is disengaged from the rails or other guides that retain the sinker to the mine-sowing vessel. On the other hand, after this rigid connection has been broken, the improved means are designed to allow a suitable length of time to elapse before separation takes place between the float and the sinker due to the buoyancy of the float. This lapse of time allows for instance the float and sinker together to sink to the bottom at the "sowing" place before the anchoring cable commences to unwind.

The manner in which this invention is to be performed will now be more particularly described with reference to the accompanying drawings which illustrate by way of example two forms of the invention. In these drawings:—

40 Figure 1 is a side elevation of a mine provided with the improved means of connecting the float to the sinker and of retarding the separation between these two elements.

Fig. 2 is a vertical section on the line 45 II—II of Fig. 1.

Fig. 3 is a vertical section on the line III—III of Fig. 2 of the means for retarding the separation.

Fig. 4 is a vertical section of a modified 50 form of the improved retarding means.

As shown, A is the mine float. B is the sinker. The sinker is provided on its sides with rollers G by means of which it is normally held and is guided at the moment of 55 "sowing", on rails R of the sowing vessel.

The improved means for assuring a rigid connection of the float A to the sinker B up to the instant when for the purpose of "sowing" the mine, the sinker is disengaged from the rails R, consists essentially in a catch mechanism the internal or external parts of which are carried by the float, either directly or by any suitable support fixed to the latter, while the corresponding external or internal parts are carried by a swing-tree arrangement which is adapted to be tilted and which is kept locked by one of its levers bearing upon the guide of the sinker or upon a separate guide. This tilting swing-tree arrangement may in practice consist of a simple bent lever or bell crank lever or equivalent device having a horizontal limb adapted to oscillate in the sinker or in the float, and having its inclined outer limb or limbs locked by their bearing upon the guide rails.

In the example shown, the catch mechanism comprises, on the float, two external parts such as eyes a. The corresponding internal parts consist of hooks C fixed on the horizontal limb D of the bent lever D—E journaled in bearings d on the sinker. The inclined limb E of the said lever, outside the sinker, bears with its free end e by means of a roller or a set screw F, upon the 85 guide rail R.

It is obvious that an inclined lever such as E, may be provided at each end of the limb or axle D carrying the hooks C.

On board the vessel, for the purpose of 90 fixing the float to the sinker, it is sufficient to screw the screw F down upon the rail and to lock it by means of its lock nut. The end of the screw may be formed with a head carrying a roller.

When for the purpose of "sowing" the mine, the mine is pushed by means of a known mechanism in such a manner as to disengage it from the rails, and consequently to release it from the mine-sowing vessel, 100 the screw F will rub along the rail R. At the instant the mine arrives at the end of this rail the lever E will be freed. Owing to its buoyancy the float will exert a pull upon the hooks C, whereby the latter will 105 be caused to turn and become disengaged from the eyes a.

The means for delaying the separation between the disengaged float and the sinker consists essentially of a cord of suitable 110

length, of which one end is attached to the float A while the other end is attached to or engaged with a piston adapted to move with slight friction in a cylinder fixed to 5 the sinker, the arrangement being such that the pressure upon the outer face of this piston will act in opposition to the force of buoyancy tending to separate the float from the sinker; this action operates only until 10 the piston or the connection between the latter and the cord is moved out of the said cylinder.

As shown in Figs. 2, 3 and 4, the cord J may be attached to the eye α^1 carried by 15 the float to which there is also attached the usual anchoring cable H which is wound on the windlass I.

In the example shown in Fig. 3, the cord J passes through a conduit K carried by 20 the sinker, and it terminates in a ball held between two jaws M that are pivoted at m to a piston O adapted to slide with slight friction in a cylinder N formed or fixed in the sinker B.

25 In the modification shown in Fig. 4, the cord J is attached directly to the piston O working in the cylinder N.

When in "sowing" the mine the hooks C are disengaged from the eyes α , the float 30 will remain prevented from separating suddenly from the sinker until the piston O shall have advanced a sufficient extent toward the open end of the cylinder N, to allow of the jaws M opening and allowing 35 the ball J to escape. This ball is guided in the conduit K until it passes out of the sinker. In the example shown in Fig. 4, the separation is delayed until the piston O passes out entirely from the cylinder N.

40 It is to be understood that the construction of the bent lever D—E or equivalent device and also of the internal or external parts of the catch mechanism, may be suitably modified.

45 Further, the bent lever or bell crank lever or equivalent device may, instead of being journaled in the sinker, be journaled in a support fixed to the float. In such a case the sinker will alone carry the internal or 50 external parts corresponding to the internal or external parts carried by the said lever or equivalent device.

It is to be understood that the free ends of the inclined limbs E of the levers or 55 equivalent devices may bear upon a separate guide, instead of bearing upon the guide R of the sinker.

It is also to be understood that the internal or external parts of the catch mechanism of the float may, instead of being 60 mounted directly on the float, be carried by any suitable part attached to the said float; for instance these parts of the catch mechanism may be carried by a part fixed 65 to the device for delaying the separation,

such as the piston O for example, in which case the tilting swing-tree arrangement would be carried by the sinker.

Having now described my invention what I claim as new and desire to secure by Let- 70 ters Patent is:—

1. In combination, a submarine mine adapted to be launched from a mine-sowing vessel and including a float and a sinker, rails mounted on the vessel to receive said 75 mine, a tilting member carried by one of said mine parts and having a locking engagement with said other mine part, said member being normally held in locking position by engaging one of said rails. 80

2. In combination, a submarine mine adapted to be launched from a mine-sowing vessel and including a float and a sinker, rails mounted on the vessel to receive said 85 mine, a tilting member carried by one of said mine parts and having a locking engagement with said other mine part, said member being normally held in locking position by engaging one of said rails, a flexible connection between the float and sinker 90 one end of which is fast to one of said mine parts and the opposite end having a releasable connection with the companion mine part, and means acting in opposition to the buoyancy of said float to delay release of 95 said connection.

3. In combination, a submarine mine adapted to be attached to a mine-sowing vessel and including a float and a sinker having an extensible connection therewith, 100 rails on the vessel to receive said mine, and catch mechanism mounted on one of said mine parts and held in locking engagement with the other mine part by one of said rails. 105

4. In combination, a submarine mine adapted to be launched from a mine-sowing vessel and including a float and a sinker, a tilting member carried by one of said mine parts and having a locking engagement 110 with said other mine part, said member being normally held in locking position by engaging a stationary part of the vessel.

5. In combination, a submarine vessel including a float, a sinker having an extensible connection therewith, guide rails fast to the deck of a vessel and in which the sinker is confined to move, a revoluble member mounted on the sinker and having at one end a latch adapted to engage said float and 120 provided at the opposite end with an arm normally bearing on one of said rails to restrain said latch from releasing the float from the sinker while the arm engages said rail. 125

6. In combination, a submarine mine including a float, a sinker having an extensible connection therewith, guide rails fast to the deck of a vessel in which the sinker is confined to move, a revoluble member 130

mounted on one of said mine parts and having at one end a latch adapted to engage the companion mine part, the opposite end of said member being provided with an arm having a set-screw bearing on one of said rails to restrain said latch from releasing the float and sinker.

In testimony whereof I have signed this specification in the presence of two subscribing witnesses.

EUGÈNE SCHNEIDER.
